(57) CLAIM

The ornamental design for a banana hanger, as shown and described.

DESCRIPTION

FIG. 1 is a perspective view of a banana hanger according to my invention.

FIG. 2 is a rear view of the banana hanger.

FIG. 3 is a top plan view of the banana hanger.

FIG. 4 is a right side view of the banana hanger; the left side view of the banana hanger is a mirror image of the right side view of the banana hanger.

FIG. 5 is a bottom plan view of the banana hanger; and,

FIG. 6 is a front view of the banana hanger.
